UNITED STATES PATENT OFFICE.

GEORGE W. WILMOT AND FRANCIS H. BLATCH, OF HAZLETON, PENNSYLVANIA, ASSIGNEES TO WILMOT ENGINEERING COMPANY, OF HAZLETON, PENNSYLVANIA, A CORPORATION OF PENNSYLVANIA.

COAL-WASHING APPARATUS.

Application filed June 14, 1922. Serial No. 568,124.

To all whom it may concern:

Be it known that we, GEORGE W. WILMOT and FRANCIS H. BLATCH, citizens of the United States, and residents of Hazleton, in 5 the county of Luzerne and State of Pennsylvania, have invented an Improvement in Coal-Washing Apparatus, of which the following is a specification.

Although we shall describe our invention 10 as embodied in apparatus for washing coal and separating slate, stone, and the like therefrom, it will be understood that said invention is adapted to be applied to and embodied in apparatus for washing other 15 materials, such as ore.

The general object of the invention is to provide a novel arrangement of a stationary jig pan and means for forcing a current of water therethrough whereby the separation 20 of the coal from foreign material, such as slate, stone, and the like, is effected efficiently,—particularly in the case of smaller sizes or grades of coal.

A further object of the invention is to 25 provide means carried partly by the stationary jig pan and partly independently thereof for creating and positively forcing a current of water through the perforated bottom of the jig pan and upwardly through 30 said pan and through the material therein to be washed.

Other objects and advantages of the invention will be pointed out in the detailed description thereof which follows or will 35 be apparent from such description.

In order that the invention may be readily understood and its practical features of advantage fully appreciated reference may be had to the accompanying drawing in which 40 a preferred form of mechanical embodiment of the apparatus is shown.

In the drawings:

Fig. 1 is a top plan view of apparatus (a portion thereof being broken away) embodying our invention;

Fig. 2 is a transverse sectional view taken on the line 2—2 of Fig. 1;

Fig. 3 is a vertical longitudinal sectional view taken in a plane at right angles to the 50 plane in which Fig. 2 is taken;

Fig. 4 is a fragmentary transverse sectional view of a portion of the jig pan and of the means for creating and forcing a current of water through said pan;

Fig. 5 is a top plan view of a portion of the valve mechanism of a reciprocating plunger situated underneath the jig pan bottom;

Fig. 6 is a longitudinal sectional view of the portion of the valve structure shown in 60 Fig. 5 taken on the line 6—6 of said figure;

Fig. 7 is a transverse sectional view of the portion of valve structure shown in Fig. 5 taken on the line 7—7 of said figure;

Fig. 8 is a top plan view of a portion of 65 a stationary valve structure situated intermediate the jig pan bottom and the valve mechanism of the plunger; and

Fig. 9 is a longitudinal sectional view of 70 one end portion of the part of the stationary valve structure shown in Fig. 8.

Referring to the drawings: 1 designates, as a whole, the frame structure by means of which the tank, designated as a whole by the reference numeral 2, is supported. Situated within the tank, which is adapted to contain water, is a stationary jig pan 3 supported in any suitable manner and by any suitable means upon the tank structure 2. The coal, ore or other material to be washed 80 is delivered into the tank through a chute 4 into the space between one end of the said pan and an adjacent adjustable baffle-plate 5 of known construction. The bottom of the jig pan is inclined toward the discharge 85 end of the apparatus, as indicated in Fig. 3, and a part of one side portion thereof adjacent its rear or discharge end is inclined inwardly, the inner edge of such inclined portion terminating adjacent the inner end of 90 the relatively narrow slate discharge opening 10. The purpose of providing the bottom of the jig pan with such inclined part or portion is to direct the slate and other relatively heavy material toward the opening 10 through which it is adapted to be discharged from the pan.

The coal or other material, which is of less specific gravity than the slate or other impurity, is maintained by the action of the 100 water within a region or zone above that of the heavier material and is discharged from the pan through the discharge chute 15 in known manner. The coal or other material so discharged is received and taken up by 105 the conveyer or carrier 16 by which it is conveyed from the apparatus and discharged. A forwardly and downwardly in-

clined shield or baffle-plate 17 is situated above the opening 10 provided for the discharge of the slate or other impurities. The purpose of such shield or baffle-plate is to effect a more efficient separation of the coal or other material of less specific gravity from the slate or other impurity of greater specific gravity.

The height of the opening 10 is adapted to be adjusted and varied by means of the adjustable breast plate 20 which is situated on the inside of the stationary end plate 21 of the jig pan. Adjustment of the plate 20 is effected by means of the rotatable adjusting screw rod 22. The slate which passes through the opening 10 piles up and finally flows over the upper edge of the adjustable plate 25 having connection with a screw threaded adjusting rod 26. By varying the height of the plate 25 the height to which the slate is caused to pile or bank up intermediate the said plate and the opening 10 may be varied; also by adjusting the said plate the speed with which the slate escapes from the jig pan is controlled.

Frequently accompanying the slate will be found sulphur and other compounds which are heavier than the slate and it is desirable that these be permitted to escape through an opening underneath the plate 25. Such an opening is provided, as indicated at 30, and its height is adapted to be varied or adjusted by means of the adjustable plate 31 situated upon the inside of the stationary plate 32 upon which both the plate 21 and the plate 25 is supported. Adjustment of the plate 31 is effected by means of the screw threaded adjusting rod 33. The upper end portions of the rods 22, 26, and 33 are supported in bearings 35 which in turn are supported upon cross bars 36 extending between the top side members 37 of the frame 1.

The slate and other material which may be discharged through the opening 10 are delivered to a conveyer 40 and are conveyed thereby from the tank 1 and discharged in known manner. The conveyer 40 is inclosed within a casing 41 so as to prevent the slate and other material from escaping from the conveyer. The conveyer 46 is likewise partially inclosed by a casting 42 for the same purpose.

Any material which may not be conveyed away by the conveyers collects in the bottom of the truncated projection or boot 45 leading from the tank from which it may be discharged through an opening controlled by a valve 46, in known manner.

For the purpose of creating and forcing a current of water upwardly through the perforations in the bottom of the tank we have secured to the tank underneath the bottom thereof the depending chamber 50, the lower end of which is open. The up-

per front and rear portions of the said chamber are flared or inclined forwardly and rearwardly, as indicated at 51 and 52, in order that the water which is forced upwardly through the chamber 50 may also enter the bottom of the jig pan 3 at points adjacent its forward and rear ends.

The chamber 50 is provided a considerable distance above its lower end with a stationary plate 55 having openings there-through which are controlled by ball valves 56 which are held within cages comprising upright posts or lugs 57, the said posts being arranged with respect to the openings as shown in Fig. 8 of the drawing. These openings are arranged in rows, as indicated also in Fig. 8, and bars 60 supported adjacent the upper ends of certain of the posts, as shown, retain the balls within the respective cages formed by the posts. These bars are situated a short distance above the ball valves 56 so that the latter may be moved upwardly to open the openings within the plate 55 by the pressure of water upwardly against the same as will be hereinafter described.

For the purpose of forcing water upwardly through the valve controlled openings within the plate 55 we have provided a valve structure designated as a whole by the reference number 65, the opposite sides of which structure are provided with downwardly extending brackets 66 which are secured to depending bars 68 connected at their upper ends to eccentrics 69 upon a shaft 70 supported in bearings upon the side members 37 of the frame 1. The valve structure 65 comprises a rectangular shaped frame member designated as a whole by the reference number 80, which frame member is provided with a laterally extending flange like portion 81. The brackets 66 are secured to the underside of the said frame member 80, as is shown in Fig. 2 of the drawing. A plurality of rectangular shaped plate members 82, two in the present instance, extend longitudinally of the apparatus and are provided with offset flange like portions 83 at their opposite ends which rest upon the upper sides or edges of the opposite end portions of the frame 80. Plates or bars 85 are situated above the frame member 80 and the inner underneath portions thereof are cut away as indicated and rest upon flanged end portions 83 of the members 82. These parts 80, 83 and 85 are secured together by means of bolts 87. The outer edges of the flanges 81 and of the bars 85 are situated in adjacent relation to or in contact with wear plates 88 which are situated upon the inner surface of the lower portion of the chamber 50. Bearing bars 89 are situated within the space between the flange 81 and the plates or bars 85. Arranged at right angles to the plates or bars 88

85 are similar plates 90 which are secured at their inner edges to the top edges of the side of the frame member 80. Located in the spaces between the said plates 90 and 5 the flange like portions 81 are bearing bars 91 arranged at right angles to the bearing bars 89 previously referred to. Openings or passageways through the frame like member 80, as indicated at 93, are provided 10 so that upon upward movement of the valve structure water is forced outwardly therethrough to press the bearing members 89 and 91 against the wear plates 88. The members 82 are provided with elongated openings 98 extending therethrough which openings are arranged in couples and in longitudinal alinement with each other, as shown in Fig. 5. The inner ends of these openings are separated or spaced from 15 each other, as shown in Fig. 7. Situated upon opposite sides of these openings are short upwardly extending flanges 99 from which project at intervals posts 100. These posts are situated on opposite sides of the 20 openings 98, as shown. These posts are relatively wide, as indicated in Figs. 5 and 6, and are provided near their tops with openings 101 through which extend rods 102. The purpose of these rods is to retain 25 cylindrical tubular members 103 in position above the elongated openings 98. The opposite ends of these tubes are adapted to be closed in any suitable manner. In the construction, as illustrated, a single valve tube 30 104 is provided for each couple of openings 98. In other words, each valve tube is of a length to co-operate with the inner edges of the flanges 99 upon opposite sides of each opening 98 of each couple. 35

40 For the purpose of strengthening the plates they are provided with ridges 105 which extend transversely thereof and which are situated between the inner ends of the openings constituting the respective couples. 45 Slush openings 106 are provided at intervals in the valve plates 82 intermediate the valve controlled openings 98.

In the operation of the device the valve structure designated as a whole by the reference number 65, as above stated, is reciprocated by reason of its connection with the bars 68 which are connected with the eccentrics 69. Rotation of these eccentrics causes reciprocation of the bars 68 and consequent 50 reciprocation of the valve structure 65 within the lower end portion of the chamber 50. Upon descent of the said valve structure the upward force or pressure exerted by the water against the tubular valve members 104 55 opens the same and permits the water to flow through the openings 98. It will be seen that the space between the valve structure 65 and the valve structure comprising the plate 55 and valves 56 becomes filled with water. 60

65 The valves 56 occupy closed positions during the descending movement of the valve structure 65. Upon upward movement of the valve structure 65 the valve rods 104 close so that the water within said space is forced upwardly through the openings in the valve plate 55. The valves 56 at such time are moved upwardly by the pressure of the water against the same. The water which thus flows upwardly through the openings in the plate 55 is forced upwardly 70 through the perforations in the bottom of the jig pan 3 and ultimately flows out through the chute 15 and possibly over the edges of the said pan. The presence of the valve structure comprising the valve plate 55 and valves 56 prevents a recession or return flow of the water through and from the pan upon descending movement of the valve structure 65. It will be seen, therefore, that the flow of water through the jig pan is constantly upwardly and forwardly and that there is no reverse flow. The result of maintaining such upward and forward flow is to bring about a more efficient action of the apparatus in effecting the separation of coal, 85 slate, etc., from each other. 90

It will be understood that in some cases it may be found desirable to omit the valve structure comprising the plate 55 and the valves 56 and operate the apparatus with the reciprocating valve structure only. 95

The coal ingredient of the mixture being of less specific gravity than other portions thereof moves toward the top of the water and is discharged through the chute 15 while 100 the slate and other material of greater specific gravity tends toward the bottom of the jig pan and finally settles upon such bottom and flows out through the opening 10 hereinbefore described. 105

Having thus described our invention what we claim and desire to secure by Letters Patent is:

1. In a coal washing apparatus, the combination of a tank, a stationary jig pan situated within said tank and provided with a chamber upon its underside, the lower end of which opens into said tank, a valve structure associated with the lower end portion of said chamber, means for reciprocating said valve structure, and a stationary valve structure situated within said chamber between the reciprocating valve structure and the bottom of the jig pan. 110
2. In a coal washing apparatus, the combination of a tank, a stationary jig pan in said tank having perforations in the bottom thereof, a chamber situated within said tank directly underneath the bottom of said jig pan, a reciprocating automatically acting valve structure situated and adapted to reciprocate within the lower end portion of said chamber, and an automatically acting stationary valve structure situated within said chamber between the said reciprocating 120
- 125
- 130

valve structure and the bottom of said jig pan.

3. In a coal washing apparatus, the combination of a jig pan having a perforated bottom, a chamber situated directly underneath the said jig pan, the upper portions of the forward and rear walls thereof being inclined forwardly and rearwardly, wear plates situated upon the inner sides of the lower end portions of said chamber, a reciprocating valve structure situated within said chamber and having bearing blocks secured in the outer edge portions thereof which are adapted to be pressed against the said bearing plates upon upward movement of said valve structure, a stationary plate secured within said chamber a distance above said reciprocating valve structure, which plate is provided with openings therethrough, valves for opening and closing said openings, and means for retaining the said valves in operative relation to said plates and the openings therein.

4. In a coal washing apparatus, the combination of a stationary jig pan having a perforated bottom, a chamber secured to said pan situated directly underneath the bottom thereof, the lower end portion of said chamber comprising vertical parallel walls and the upper portion of the forward and rear walls being inclined forwardly and rearwardly, a rotatable shaft, eccentrics on said shaft, a valve structure situated in the lower end portion of said chamber, connections between said eccentrics and said valve structure for supporting the latter whereby upon rotation of the said eccentrics the said valve structure will be reciprocated, and a stationary valve structure situated within the said chamber between the reciprocating valve structure and the bottom of said pan. 30 35 40

In testimony that we claim the foregoing as our invention we have hereunto signed our names this 3rd day of June, 1922.

GEORGE W. WILMOT.
FRANCIS H. BLATCH.
